UNITED STATES PATENT OFFICE.

HARRY S. JONES, OF CHICAGO, ILLINOIS.

STEEL-STOCK RACK.

Application filed June 22, 1923. Serial No. 647,095.

This invention relates more particularly to an improved type of a steel stock rack wherein a plurality of knock-down rack sections are adapted to be independently assembled and positioned adjacent one another as needed, to form a continuous rack adapted to permit stock steel to be stored according to size in channel troughs forming part of said sections.

- 10 It is an object of this invention to provide a stock rack adapted to be increased or decreased in size to regulate the capacity of said rack according to the amount of the stock on hand.
- 15 It is also an object of the invention to provide a steel stock rack wherein each section embraces a plurality of stock carrying channels supported by frame sections constructed of removably connected H-frames.
- 20 Another object of the invention is the construction of a steel stock rack adapted to be increased or decreased in size to vary the floor space occupied by the rack proportionately to the amount of the stock to be carried by the rack.

It is a further object of the invention to construct a steel stock rack adapted to be increased in size either vertically or horizontally as desired.

- 30 It is an important object of this invention to provide a stock rack of variable capacity for carrying stock steel rods or bars of various sizes in different channel troughs supported by knock-down uprights.
- 35 Other and further important objects of this invention will be apparent from the disclosures in the specification and the accompanying drawings.

The invention (in a preferred form) is illustrated in the drawings and hereinafter more fully described.

On the drawings:

Figure 1 is an end elevation of a steel stock rack embodying the principles of this invention.

Figure 2 is a top plan view thereof.

Figure 3 is a front elevation of the rack broken away at one end.

Figure 4 is a detail front elevation of one of the large H-frame units with a stock carrying channel seated therein.

Figure 5 is a section taken on line 5-5, of Figure 4.

Figure 6 is a section taken on line 6-6, of Figure 4.

Figure 7 is a detail front elevation of one

of the small H-frame units having a stock carrying channel seated therein.

As shown on the drawings:

The rack is adapted for carrying stock steel rods or bars assorted according to size in channels or troughs forming part of rack sections positioned adjacent each other in any desired number.

Each rack section comprises a plurality of spaced uprights, supports or standards each embracing a plurality of frame units removably secured by means of bolts 1, one above the other to any desired height. The frame units may be formed in different heights as shown in Figures 4 and 7, and each embraces two spaced parallel channel arms 2, the integral flanges 3 and 4, of which are provided with openings 5, disposed on opposite sides of an integral reinforcing web 6, which is in the middle of the channel arm and extends from flange to flange thereof. The two channel arms 2, are integrally connected, to form a one-piece H-frame unit, by means of a T-cross-sectioned cross-piece 7 or supporting bar 7. Openings 10 are provided in the arm webs 6. The supporting bar 7, of each frame unit connects the lower portions of the parallel side arms 2, to afford a U-shaped recess or pocket above said bar 85 for removably receiving seated therein a channel or trough 8. The side flanges of each trough are of a height to extend upwardly to the upper arm flanges 4, as shown in Figures 4 and 7. The various channel troughs 8, extend through a plurality of aligned frame units which serve to support said troughs 8, in position one above the other to form a single steel stock rack section.

Figure 1 shows an elevation of an end stock rack section, the end supports or uprights of which are removably secured together or braced by diagonal connecting or tie rods 9, which cross each other diagonally at an intermediate upright. As shown in Figure 2, the uprights of adjacent rack sections are offset and overlapped as to their channel arms 2 to permit closer association of the various sections making up the rack. The outer sides of the end sections are preferably the only frame section sides provided with crossed reinforcing connecting rods 9, the ends of which are bolted through openings 10, provided in the webs 6, of the frame units.

As shown in Figure 2, the steel stock

rack is composed of a plurality of adjacently disposed independently constructed rack sections, the upright supports of which are offset to overlap one another to permit closer association of said sections, thereby minimizing the amount of floor space occupied by the rack. The H-frame units may be constructed of different heights as shown in Figures 4 and 7, to support stock carrying channel troughs of different depths. The channel troughs 8, are arranged to receive and hold steel rods or bars assorted into different sizes. Each rack section is adapted to be independently increased in height by adding on additional H-frame units and seating channel troughs therein. The troughs 8, may be removably secured in place if desired.

Any number of rack sections of the same or different heights may be placed adjacent one another in aligned series with their channel arms 2 overlapping, as shown in Figures 2 and 3, to provide a steel stock rack of any desired capacity. When the stock carried by the rack has been materially reduced, the remaining stock may be stored in a few sections to permit the empty sec-

tions to be dismembered, and the parts stored away in knock-down form. The floor space formerly occupied by the emptied rack sections is thus reclaimed and may be used for other purposes, until the stock is again increased to such an extent that additional stock rack sections are required.

I am aware that numerous details of construction may be varied through a wide range without departing from the principles of this invention, and I therefore do not purpose limiting the patent granted otherwise than necessitated by the prior art.

I claim as my invention:

A stock rack comprising a plurality of superimposed detachably connected self-supporting sections, each section embracing a plurality of one-piece H-frame units having side channel members, said units being disposed in a plurality of aligned series with their channel members overlapping, and stock troughs removably seated in said aligned units for receiving stock steel.

In testimony whereof I have hereunto subscribed my name.

HARRY S. JONES.
